DESIGN FOR AN EMBROIDERED TRIMMING OR THE LIKE

Robert Senderowitz, Allentown, Pa.

Application August 25, 1942, Serial No. 108,030

Term of patent 3½ years

To all whom it may concern:

Be it known that I, Robert Senderowitz, a citizen of the United States of America, residing in Allentown, county of Lehigh, and State of Pennsylvania, have invented a new, original, and ornamental Design for an Embroidered Trimming or the like, of which the following is a specification, reference being had to the accompanying drawing, forming part thereof, wherein the figure of the drawing is a plan view of an embroidered trimming or the like, showing my new design.

I claim:

The ornamental design for an embroidered trimming or the like, substantially as shown.

ROBERT SENDEROWITZ.
